(57) CLAIM

The ornamental design for a toy track with platform, as shown and described.

DESCRIPTION

FIG. 1 is a first perspective view of a toy track with platform showing the top, front, and right side views of our new design; FIG. 2 is a front side view thereof; FIG. 3 is a rear side view thereof; and, FIG. 4 is a top plan view thereof.

The broken lines are for environmental purposes only and form no part of the claimed design.
